UNITED STATES PATENT OFFICE.

WILLIAM E. WATKINS, OF NEW YORK, N. Y., ASSIGNOR TO THE METALS PLATING COMPANY, OF NEW YORK, N. Y., A CORPORATION OF NEW JERSEY.

COATING-MACHINE.

1,295,819.

Specification of Letters Patent. Patented Feb. 25, 1919.

Original application filed June 10, 1916, Serial No. 102,977. Divided and this application filed June 29, 1916. Serial No. 106,564.

To all whom it may concern:

Be it known that I, WILLIAM E. WATKINS, a citizen of the United States, residing in the city, county, and State of New York, have 5 invented certain new and useful Improvements in Coating-Machines; and I do hereby declare the following to be a full, clear, and exact description of the invention, such as will enable others skilled in the art to 10 which it appertains to make and use the same.

The invention comprises a machine whereby sheets of elastic metal, such as iron or steel, may be coated on one or preferably on 15 both sides with a liquid or semi-liquid, and more particularly a viscous mixture or composition. This coating may be of such a character that on subsequent heat treatment under proper conditions, it will yield a permanent non-stripping, firmly adherent metal 20 plating on the underlying metal.

The invention also comprises mechanism for bending or curving the sheets of elastic metal before heat treatment so that each assumes an arched shape, and for advancing or 25 transferring the arched sheets toward the furnace, and for delivering them, properly timed, to the conveyer by which they are to be transported to the furnace for heat treatment.

The invention also comprises apparatus for reliably transporting the arched sheets to and through the heating furnace while in arched form, and for finally delivering them 35 for such further treatment as they may require.

The coating machine, the bending, transferring and delivery mechanism, and the transporting apparatus may all be driven by 40 a common source of power, and as the result of their joint and co-operative action, flat sheets of metal, more particularly elastic metal (such as iron or steel), may be covered with a uniform layer of viscous coating, out of which, by subsequent and proper 45 heat treatment, there may be formed on the underlying metal, a firmly adherent and non-stripping plating, as of copper.

The details of one embodiment of the 50 present invention will be made clear by the following detailed description, which illustrates the utility of the invention with particular reference to the plating of sheet iron,

or steel, with copper, but I am aware that certain parts of the apparatus are of utility 55 when the articles to be treated are not in the form of sheets, and are not elastic, and are not ferrous metal, and are to be plated with material other than copper, and it will therefore be understood that in illustrating 60 and describing the preferred embodiment of the invention, I do not limit myself thereto, but contemplate the employment of such other like devices in the several combinations and sub-combinations set forth, as fairly 65 fall within the scope of the appended claims.

In the accompanying drawings, forming a part of this specification—

Figure 1 is a side elevation of the machine as viewed from the left; 70

Fig. 2 is a detail of the feeding mechanism as viewed from the right;

Figs. 3 and 4 are details of the adjusting means for the coating rolls;

Fig. 5 is a side elevation on a somewhat 75 larger scale, showing the machine as viewed from the right;

Figs. 6 and 7, placed end to end, constitute a plan view partly in section on the line 6—7 of Fig. 5; 80

Fig. 8 is a sectional elevation on the line 8—8 of Figs. 6 and 7;

Fig. 9 is a plan of the pump mechanism which has been omitted from Fig. 6 for clearness in illustration; 85

Fig. 10 is a transverse section on the line 10—10 of Fig. 6;

Fig. 11 is a transverse section through the machine on the broken line 11—11 of Fig. 5;

Fig. 12 is a section on the line 12—12 of 90 Fig. 6, showing the drive for the converging conveyers;

Fig. 13 is a section on the line 13—13 of Fig. 6, illustrating the arched face of the sheet as it leaves the transfer mechanism of 95 the coating machine;

Fig. 14 is a section on the line 14—14 of Fig. 8;

Fig. 15 is an enlarged view showing the chain guides for the pusher near the top of 100 Fig. 8;

Fig. 16 is a plan view of the pusher;

Fig. 17 is an enlarged detail of a part of the converging elements used for bending the sheets; 105

Figs. 18 and 19 illustrate one of the slotted

pipes whereby the coating composition is supplied to its distributing roll for delivery to a coating roll; and

5 Figs. 20, 21, 22 and 23 are details of the furnace conveyer.

The first step in the method for which my present invention is particularly intended consists in applying to the articles to be plated (such as iron or steel), a coating out 10 of which by suitable heat treatment, the permanently adhering or non-stripping plating (such as copper) can be formed.

The material for use as this initial coating may vary. It should be sticky or viscous 15 enough to adhere well to the sheets and should have body enough to form a smooth, even layer of uniform thickness. It should not drip or run, and of course must be so chemically constituted as to yield a plating 20 metal when subsequently treated, as by heating. I may use a reducible compound of the plating metal held in suspension in a suitable vehicle, such as a viscous reducing agent, this suspension constituting a 25 paste or semi-liquid mixture adapted to be spread in an even, dense, compact layer upon the metal to be plated. Thus, I may use 30 oxid of copper (CuO) ground to great fineness in a heavy oil, such as a mixture of equal parts of Mexican crude oil and a native fuel oil. Mexican crude oil is particularly appropriate because it has an asphaltic base and yields a residue of carbon on 35 destructive distillation. In the subsequent 40 furnace treatment, this carbon serves as a reducing agent for the metal compound present in the mixture. But Mexican crude oil alone is frequently too viscous, and an admixture of native fuel oil is desirable to 45 lower the viscosity, even though it may all, or nearly all, vaporize off during the heat treatment, and without greatly contributing to the carbon residue. In compounding such a coating mixture the reducible 50 compound of the plating metal, such as oxid of copper, must be present in such quantity that on subsequent reduction it will yield a copper plating of requisite thickness.

I have found in practice that there is a 55 limitation upon the amount of plating metal that can readily be applied by this method in a single furnace treatment. This limitation is in part due to the required viscosity of the applied coating and in part to the fact that 60 a certain proportion of the metal compound escapes reduction because of insufficient reducing power of the reducing vehicle. As a consequence, not only is the quantity of plating metal correspondingly diminished, but 65 a portion of the reducible compound escapes reduction and must be removed from the plating surface upon which it tends to collect.

Therefore, to enhance the efficiency of the 70 process, I prefer to add as a constituent of

the paste or suspension of the reducible compound and its liquid vehicle, an appropriate quantity of a finely divided solid reducing agent, such as finely divided carbon. The resultant mixture will still have the requisite viscosity and will also have its reducing power so increased that the metal of the reducible compound may be deposited in its substantial entirety as plating metal upon the metal to be plated.

70

75

A suitable composition for the initial coating may be made by grinding together one part by weight of copper oxid, one part by weight of Mexican crude oil (having a specific gravity represented by $7\frac{3}{4}$ pounds to the 80 gallon) and $\frac{1}{16}$ th to $\frac{1}{8}$ th part by weight of finely divided carbon as for instance, lamp black. Such a mass will have a viscosity sufficient to permit it to be applied by coating rolls of the type shown in Fig. 1, and 85 when so applied will form a dense adhesive, uniform layer upon both sides of the iron or steel sheet.

80

85

It is possible to enrich such a coating mixture by grinding into it say one part by 90 weight of finely divided metallic copper. The viscosity will still be satisfactory, and this additional copper will supplement that resulting from reduction of the copper oxid and so yield a plating of corresponding increased thickness.

95

Instead of Mexican crude oil, I may use a lighter hydrocarbon, such as kerosene, or I may even employ water as the spreading vehicle, but, in these instances, I increase the 100 amount of finely divided carbon employed so that there may be enough carbon present to effect complete reduction of the oxid and to afford adequate protection to the melted, or 105 nearly melted, copper.

105

Also, I have discovered that it is possible to dispense entirely with the reducible compound and that the copper or other plating metal may be applied to the iron or steel sheet as finely divided metal, preferably obtained by precipitation or reduction, in connection with a suitable distributing vehicle capable of holding the metal in position until it melts and forms a non-stripping plating. Finely divided solid carbon, such 110 as lamp black, may be present to protect against oxidation, when necessary, and in addition, or as a substitute for the solid carbon, a fluid hydrocarbon, such as kerosene or a viscous hydrocarbon, such as Mexican crude oil, may serve as the vehicle itself.

115

120

125

The next step in the process, whatever may be the exact composition of the initial coating, consists in bending each coated sheet after it emerges from the coating rolls, so that it assumes the form of an arch, and this I am able to do by the apparatus of Fig. 1, without disturbing the continuity of the initial coating, by the effective expedient 130

of giving the sheet an upward bend or hump in the middle, particularly at its front edges, and then pressing inward on its edges until the sheet bows up and assumes the desired arched form. The whole operation is automatic in the apparatus of Fig. 1, and the sheet is then ready for forwarding to the furnace for the necessary heat treatment.

The next step is the heat treatment within the furnace, whereby the initial coating yields a non-stripping or firmly adherent plating on the underlying iron or steel or the like. The furnace wherein this treatment is carried out need not be described here in detail, but in it the sheets as they pass through on an endless conveyer and in arched form are heated in a reducing environment to a temperature and for a time sufficient to produce such reduction of melting, or both, as may be necessary to form the plating from the materials of the initial coating. The arched sheets thus treated are finally delivered from the conveyer for such flattening and further treatment as they may require.

25 The coating machine comprises a frame 100, and is provided at the front with an apron or feed table 101 on which the sheets to be coated are dropped by hand and from which they are automatically fed into the 30 coating rolls.

The automatic sheet feeding mechanism comprises three stops 102 (Figs. 6 and 10), in the form of rollers which project above the feed table, and may rotate about their respective axes while contacting with the edge of a sheet during its forward movement. As means for holding the sheet against these rollers 102 and bringing it into true alignment for passage through the machine, there is provided a roller 103 mounted on an arm 40 104, which is pivoted beneath the feed table on pivot 105, and is actuated by a link 106 adjustably pivoted to arm 104 and also pivoted to a swinging arm 107, the rear end of which is pivoted to the under-face of the feed table at 108, and the front end of which carries a roller 109 actuated by a cam 110, the movements of which are hereinafter described. A rigid and stationary reinforcing 45 strip 111 gives firm anchorage for pivots 105 and 108, and a spring 112 is connected between this strip 111 and swinging arm 104 to yieldingly urge roller 103 toward rollers 102, so that on suitable movement of cam 110, the 50 roller 103 can swing inward against the edge of a sheet that has been dropped on the table and slide that sheet over against rollers 102 and thereby bring it into proper position and alignment with respect to the coating 55 and 60 rolls.

The coating rolls 113 and 114 (Fig. 8) are faced with a layer 115 of suitable yielding composition like soft rubber. The shafts 116 and 117 for these rolls are carried in bearing blocks 118 and 119, respectively,

(Figs. 1 and 11), the lower pair of which are seated at the bottom of appropriate guideways in frame 109, and the upper pair 118 of which are adjustable up or down in that guideway to vary the distance between the 70 coating rolls 113 and 114.

The adjusting mechanism for the coating rolls comprises a pair of springs 120 (Fig. 11), located respectively within the guideways of frame 100, and positioned between 75 the adjacent bearing blocks 118 and 119 of the upper and lower roll shafts. These springs tend to hold the coating rolls separated. Above each upper bearing block 118 and contacting therewith is a stop bar 121 80 (Fig. 1), which passes freely through a cover-plate 122 (Fig. 3), except that it has a longitudinal slot 123 (Fig. 4) in which fits a key 124 (Fig. 3) rigidly mounted in cover-plate 122. The upper end of rod 121 is threaded 85 and passes freely through an enlarged opening in a worm gear 125 and has threaded engagement with a nut 126 which is adjustably and detachably connected with worm gear 125 by bolt 127 and slot 128 (Fig. 4). A 90 bracket 129 (Fig. 3), integral with cover-plate 122, forms a guide and support for the upper end of rod 121. Engaging with worm wheel 125 is a worm 130 fastened to a shaft 131 which carries an adjusting hand wheel 95 132 (Fig. 1) on the left hand side of the machine. This shaft 131 extends across to the other side of the machine (Fig. 11), for actuating another and similar worm wheel and stop bar to hold the other upper bearing 100 block against the tension of its spring 120. The upper coating roll can thus be adjusted toward or from the lower roll and each end can be independently adjusted to maintain proper spacing of the rolls throughout their 105 entire length.

The liquid composition to be supplied to the coating rolls is pumped through a transverse pipe 133 and delivered through narrow longitudinal slots and in a substantially continuous cascade or sheet to a distributing roll 134 which is accurately spaced a short distance from the uppermost coating roll 113 (Fig. 8), and is spaced slightly from an equalizing roll 135. Distributing roll 134 110 is carried and driven by a shaft 136, and equalizing roll 135 is carried and driven by a shaft 137, and the ends of these shafts 136 and 137 are fitted to bearing blocks 138 and 139, respectively, (Fig. 1). These blocks are 115 mounted in horizontal guideways as shown. A pair of springs 140 urge the distributing roll 134 away from the coating roll 113, and a similar pair of springs 141 urge the equalizing roll 135 away from the distributing 120 roll 134. Opposed to each spring 140 and 141 is a stop bar complete with nut, gears and other features, of the type shown in Figs. 3 and 4, and complete with hand wheels 142 and 143. The ends of each roll can there- 125 130

by be adjusted simultaneously or one end can be shifted independently of the other. One of these stop bars controls the distance between the distributing roll 134 and the coating roll 113, and the other controls the distance between the distributing roll and the equalizing roll 135, and jointly they control the thickness of the film of fluid which is carried forward by the distributing roll and 10 deposited on the upwardly moving face of the upper coating roll 113.

In practical operation, the coating fluid may work out to the edge of distributing roll 134 and to the edge of equalizing roll 135 and there harden to form a fin, and to prevent this troublesome accumulation, there is provided at each end of these rolls a scraper 144 in the form of a shallow, concave box, the curved bottom of which contacts with the ends of the rolls and approximately intersects their line of contact one with another, as shown in Fig. 8, and so act somewhat as a receptacle in which these incrustations may be accumulated and 25 from which they may be removed from time to time. This scraper 144 is rigidly attached to an arm 145 fastened with a set screw 146 to the fluid distributing pipe 133.

The lower coating roll 114 is similarly 30 equipped with a distributing roll 147 and an equalizing roll 148, these being adjustable, respectively, by means of hand wheels 149 and 150 (Fig. 1) acting through worm gears, stop bars, and other elements, as in 35 the case of the upper equalizing and distributing rolls. The scraper 151 for the lower distributing roll 147 is of essentially the same shape as scraper 144, but is arranged to clean the end of the lower coating roll 114 as well as its distributing roll 147, the concave bottom of the scraper 151 substantially intersecting the line of contact of these two rolls. This scraper 151 is supported from the lower fluid supply 40 pipe 152 and can be swung thereon for emptying when desired.

The coating liquid or composition is normally held in a tank 153. As the liquid may carry suspended solids, liable to settle 50 out, there is provided an agitator for constantly stirring the contents of this tank. The agitator comprises a central shaft 154 (Fig. 1) which carries a pair of propeller blades 155 suspended just above the bottom 55 of the tank and adapted particularly to prevent the accumulation of solids on the bottom. Agitator shaft 154 is supported in a bearing 156 (Fig. 9) carried by the skeleton cover 157 of the tank and removable 60 from the tank with that cover for cleaning or inspection. Agitator shaft 154 carries at its upper end a bevel gear 158 which meshes with a bevel gear 159 carried on a horizontal shaft 160, which is driven 65 through a spur gear 161. The latter is

driven in a manner hereinafter described. At the other end of shaft 160, and splined thereon, is a spur gear 162 (Fig. 9) and this meshes with a gear 163 to drive the shaft 164 of a gear pump 165 of usual construction. Shaft 164 is squared at its exposed end to receive a hand crank, and by sliding spur gear 162 outward out of mesh with gear 163, this hand crank can be used for rotating the pump to prime it, 75 or for distributing fluid in small quantity through the distributing pipes when the coating machine is not in regular operation. Gear 162 is normally held against accidental sliding movement by a set screw 166. The 80 pump 165 and its associated gearing are mounted on one arm of the removable skeleton cover 157, and so are readily removable for inspection or repair.

Pump 165 delivers the coating liquid 85 through a pipe 167 (Fig. 8) which, at its forward end, has a branch running through valve 168 to the liquid distributing pipe 162, and also a branch extending upward through valve 169 to the upper distributing 90 pipe 133. At a point approximately above tank 153 the liquid distributing pipe 167 has a by-pass through valve 170 and a pipe 171 leading to tank 153. For purposes of priming it is therefore possible to open 95 valve 170 and close valves 168 and 169, and then by hand or otherwise, pump the liquid out of tank 153 and through valve 170 back into the tank again, thereby mixing and agitating the liquid and making sure that 100 the pump is in proper operative condition. A union 172 in pipe 167 facilitates removal of tank 153 and its detachable cover, pump, gearing, and the like.

To take care of the surplus liquid, there 105 is provided beneath equilizing roller 137 a removable trough 173 (Fig. 8) which slopes (Fig. 11) to a drain pipe 174 (Fig. 8) discharging into tank 153, and, similarly, the lower equilizing roll 148 has a removable, 110 sloping trough 175 with a drain pipe 176. These two drain pipes, as well as pipe 171, are short enough not to interfere with removal of tank 153. An inclined drain plate 177 is detachably supported under the lower 115 coating roll 114 to catch the drippings and deliver them into trough 175.

Referring to Figs. 1, 5, 6 and 11 the driving mechanism for the coating machine and its supply pump is disclosed. Power is delivered through a main driving chain 178 (Fig. 5) to rotate a sprocket 179 loosely mounted on a shaft 180. The outer face of the hub of sprocket 179 is shaped to form a clutch member and an opposing clutch member 181 is splined on shaft 180 and provided with a vertical shipper lever 182, pivoted at 183 to a bracket 184, secured to the frame 100. For the purpose of actuating the clutch from the other side of the machine, there is 130

provided a connecting link 185 pivotally attached to a shipper lever 182 and to a corresponding lever 186 on the other side of the machine. The spline for clutch member 181 abuts against the hub of sprocket 179 and holds it against axial movement, and the right hand end of shaft 180 is supported in an outboard bearing 187 in the form of a bracket bolted to frame 100 (Figs. 5 and 6). The shipper lever 182 is of yoke shape (Fig. 5) to straddle shaft 180, and is attached through horizontal lugs to a split collar 188 (Fig. 11) seated in a groove of clutch member 181. The left hand end of shaft 180 carries a hand wheel so that the machine can be turned over slowly by hand, as when adjusting the timing of its several parts.

Keyed to shaft 180 is a gear 189 (Fig. 11) which meshes with a gear 190 on shaft 117 of the lower coating roll. Gear 190 meshes with a gear 191 (Fig. 5) supported on a stub carried by a bracket secured to the right hand side of the machine. Gear 191 meshes with a wide gear 192, similarly supported and the latter meshes somewhat loosely with a gear 193 on shaft 116 of the upper coating roll. Gear 193 meshes somewhat loosely with a gear 194 on shaft 136 of the upper distributing roll and drives that roll at a proper peripheral speed to effectively apply the coating liquid to the yielding face of the upper roll. Gear 194 meshes with a gear 195 on shaft 137 of the upper equalizing roll to rotate it at the same peripheral speed as the adjacent distributing roll.

The lower distributing and equalizing rolls are similarly provided with driving gears 196 and 197, respectively, and are driven from gear 190.

When the machine is in action, the power delivered through main driving chain 178 and its sprocket 179 and the co-operating clutch, drives the coating rolls 113 and 114 as indicated by arrows (Fig. 8) and a sheet of metal A, moved forward on the feed table 101, will be gripped at its forward edge by the yielding composition faces of these rolls, and drawn forward, simultaneously with the deposition on its top and bottom faces of a thin, uniform and homogeneous film of the coating liquid. One side may be left un-coated if desired.

The mechanism whereby the sheet of metal A to be coated is automatically fed forward into position to be gripped by the coating rolls, comprises a finger 198 (Figs. 2 and 6) which projects through a slot in feed table 101, and is carried by a block 199 mounted to slide in guides 200 (Fig. 10), secured to the under face of feed table 101. As a means for sliding block 199 toward and from the coating rolls, and for timing its movements, there is provided a link 201 (Fig. 2) pivoted to the block and adjustably pivoted to

a swinging arm 202, which is mounted near the center of a transverse rock shaft 203 supported by bearings on the front legs of frame 100. The right hand end of shaft 203 carries a crank 204, to the slotted end of which is adjustably connected a cam actuated thrust bar 205, which carries a roller 206 bearing against the periphery of a cam 207, and this, as shown in Fig. 11, is mounted on shaft 180 at the side of gear 189. The cam is fastened to gear 189 by a bolt 208 (Fig. 2) which can be shifted in a slot 209 to permit adjustment of the cam with respect to the gear to regulate the timing of the feed mechanism with respect to other moving elements of the machine. Thrust bar 205 has its rear end formed into a yoke 210 which embraces and slides upon the hub of cam 207 and swings thereon as it moves outward under the action of the cam. To effect inward movement of the thrust bar 205 and forward movement of the feeding finger 198, shaft 203 is provided with a downwardly extending crank 211, to the end of which is pivoted a rod 212, Fig. 5, the rear end of which passes freely through a block 213, which is mounted on the main frame and is free to swing as much as is necessary to accommodate backward and forward movements of rod 212. A compression spring 214 encircles rod 212 and bears at its rear end on block 213, and at its forward end against a tension adjusting nut 215. Outward movement of thrust bar 205 produced by action of cam 207 on roller 206 compresses spring 214 and as soon as cam 207 will permit, spring 214, by its expansion, yieldingly pulls feed finger 198 forward toward the coating rollers and thereby advances the sheet to be coated until its front edge enters between the coating rolls. The sheet-aligning mechanism for the feed table, heretofore described, is suitably timed with respect to the forward movement of finger 198 by proper location of cam 110 with respect to sliding block 199 to which it is rigidly fastened.

To drive pump 165 and its associated agitator, there is provided a sprocket 216 (Fig. 11) on shaft 117, the sprocket being bolted to gear 190. A chain 217 driven by this sprocket passes over a smaller sprocket 218 (Fig. 6) secured to a shaft 219 (Fig. 12), which extends substantially across the machine and also serves to drive the converging conveyors as hereinafter explained.

Keyed to shaft 219 is a spur gear 220 which meshes with gear 161 (Fig. 9) of the pump-driving mechanism. In this way, power is delivered to the pump.

Immediately behind the main frame 100 is an auxiliary frame 221, whereon is mounted the mechanism by which the flat sheets as they come from the coating rolls are bent

into arched form and then are forwarded and are delivered at regular and predetermined time intervals to the conveyer by which they are transported to and through the furnace of the apparatus. To the front of frame 221 are attached a pair of supports 222 and 223, which are anchored and supported at their forward ends by bolted connection with main frame 100. A single bolt 224 for each support is used, thereby serving as a hinge to compensate for slight differences in the height or alinement of the two frames. The rear end of each of these supports is similarly secured by a single bolt 225.

The means for bending each sheet into an arch, includes a plurality of rotating shafts 226, of which there may be five, as shown, having their bearings in supports 222 and 223. Each of these shafts carries a sprocket 227 and all of the sprockets are positively driven through a single chain 228 which passes over an idler 229 and is driven by a sprocket 230 (Fig. 12) mounted on shaft 219 and driven thereby. Shafts 226 are provided with star wheels or the like, preferably in the form of thin disks having sharp edges with teeth, to limit the area of their contact with the coated sheet as it is advanced over them. The star wheels 231 for the first two shafts of the series are fastened to those shafts and so are positively driven, and similarly, the four outside star wheels 232 of the next two shafts are positively driven. The two outermost star wheels 233 of the last shaft are free to rotate on their shaft, but are held against axial displacement by a pair of collars, one of which can be adjusted axially along the shaft. All of the star wheels so far described are preferably of the same diameter, but the three central star wheels 234, 235 and 236 on the three rear shafts are of progressively increasing diameters, as shown in Fig. 8, and are loose on their respective shafts. They are held against axial shifting by the collars between which they are free to rotate, and they are staggered as shown in Fig. 6.

When a coated sheet comes from the coating rolls, it is carried along by the star wheels, and their points of contact with it are so small in area as not to wipe off or deface the adhering coating to any appreciable extent. As the sheet moves along, its center rides up on the enlarged central wheels 234, 235 and 236, which are driven by the friction of the sheet thereon and thus is given a hump in the center preparatory to engagement with the converging elements which transform the sheet into a complete and symmetrical arch.

Above frame 221 and supported thereby are a pair of converging elements in the form of belts or the like 237 and 238, preferably of leather and each passing over pul-

leys 239 and 240. These pulleys are so spaced, as shown in Figs. 6 and 7, that the belts converge and collectively form a conveyer by which the sheets are received from the star wheels and are held by their edges only. The edges are then progressively squeezed inward as the sheets are advanced between the converging belts thereby converting the sheets into the desired arched form for delivery to the furnace conveyer. 75

In considering the details of the converging conveyer, reference may be had to Figs. 17, 6, 7, 8, 12 and 13.

Each of the leather belts 237 and 238 has a facing of separated metal plates or scales 241 (Fig. 17), and each of these scales has two integral legs, one of which is riveted to the belt and the other of which is L-shaped as shown to form a shelf 242 in the acute angle of which the edge of a sheet of metal under treatment may be received and under the overhanging but somewhat yielding side of which that edge is held against danger of accidental dislodgment. 80

These belts 237 and 238 are driven, respectively, by their pulleys 239 (Fig. 12). The pulleys are mounted, respectively, on vertical shafts provided with beveled gears 243 which mesh with beveled gears 244 splined on shaft 219 and driven thereby. Each of these pulley shafts passes through a bearing member 245 from which depends a downwardly extending bracket 246 terminating in a bearing 247, whereby shaft 219 is supported and the adjacent beveled gear 244 is held to working engagement with its companion gear 243. The bearing members 245 for the belt pulleys 239 are supported by a cross-bar 248 (Fig. 13). Each bearing member 245 has a slotted lug 249 equipped with a clamping stud 250 threaded into cross-bar 248. It is therefore possible to shift either of the pulleys 239 to the right or to the left, as to increase or decrease the distance between them, or to correct for misalinement 95 in the machine. 100

As a means for guiding the working sides of the conveyer belts 237 and 238, and to prevent them from sagging or from bulging outward under the spreading action of the 115 arching sheets, two angle bar guides 251 and 252 (Fig. 7) are provided on the horizontal flange of each of which the lower edge of its leather belt may slide in a shallow groove. The scales 241 of the belts also contact with and slide along these horizontal flanges (Fig. 13). Guides 251 and 252 are bolted respectively to ears 253 and 254 (Fig. 13) integral with lugs 249 of the pulley bearing members 245. Guides 251 and 252 120 have slots 255 and 256 (Fig. 6) to permit longitudinal shifting, when required, (their other ends being similarly slotted, Fig. 7) and can be swung through a small angle about the bolts 257 and 258 which pass 125 130

through these slots and anchor the guides to ears 253 and 254 (Fig. 13).

At the other end of this converging conveyer, the pulleys 240 (Fig. 7) act merely as sheaves and are mounted on vertical shafts, each of which is carried in a bracket 259 bolted to a cross-bar 260 of the supporting frame 221, and having a slot 261 at its clamping bolt to permit adjustment inward or outward to vary the distance between the two conveyer belts at the narrow end of the conveyer. Cross-bar 260 is also adjustable lengthwise of the machine to move pulleys 240 to tension the conveyer belts. This latter adjustment is effected by means of screws 262, one on either side of the machine, and threaded through studs 263 which are screwed into the top of frame 221. These screws bear against the edge 10 of bar 260 and can be used to force the bar rearwardly when the belts are to be tightened. Bolts 264 pass through slots in bar 260 and serve to anchor the bar to frame 221 after the adjustment is complete.

Beyond the narrow end of this converging conveyer is a guideway consisting of two independent bent plates 265, each of which is pivoted by a bolt 266 to a bracket arm 267. This bracket arm has a slot and clamping bolt at 268 to permit swinging adjustment of plate 265 about bolt 266. At the other end of the bracket arm 267 is a pivot bolt 269 and a clamping bolt 270, the former passing through a longitudinal slot in arm 267, and the latter through a similar slot in that arm, and also through a curved slot in cross-bar 260, so that bracket arm 267 can be adjusted longitudinally, or can be swung about bolt 269 as a center, 40 to bring its plate 265 into best relation to the delivery end of the converging conveyer. Plates 265 are thus adjustable toward or from one another to vary the width of the guideway formed therebetween.

By the apparatus above described, the sheets of metal to be treated, as they come from the coating rolls, are given an initial bend by the star wheels, and then pass along through the converging conveyer, and when 50 they issue therefrom into the stationary guide, formed by plates 265, they are in proper condition for delivery to the furnace conveyer. In order that there may be no uncertainty in their delivery from the converging conveyer to the furnace conveyer, and in order that their delivery may be definitely timed, there is provided a delivery mechanism or pusher, shown particularly in Figs. 1, 5, 8 and 16.

The pusher comprises a pair of endless chains 271 passing over driving sprockets 272 fastened to shaft 273, which is mounted in brackets 274 bolted to supports 222 and 223. This shaft carries a sprocket wheel 275 driven through a chain 276 by sprocket 277

(Fig. 11) keyed to shaft 180. Pusher chains 271 also pass over smooth flanged pulleys 278, which are loosely mounted on a shaft 279 supported by brackets 280 which are bolted at the top of frame 221 (Fig. 5). 70 These brackets have slots 281 and adjusting screws 282 to permit them to slide with respect to frame 221, and so tighten or loosen the pusher chains 271.

Chains 271 are provided with three L-shaped pushing fingers 283, each mounted on a pivot pin 284. These pivot pins tie the chains together, as shown in Fig. 15, so that they move in unison, but the chains are spaced apart far enough to permit swinging 80 movement therebetween of the shorter arm of each L-shaped finger 283, whereon a cam roller 285 is mounted. The cam surface on which these rollers 285 bear, comprises a top plate 286 (Fig. 8), a bottom plate 287, 85 and a stationary curved casting 288, mounted on shaft 279. This casting serves as a space block for the two chain pulleys 278 and is connected by slots and bolts to plates 286 and 287 to permit longitudinal 90 adjustment of these plates, when desired, as when brackets 280 are shifted to tighten or loosen the chains 271.

Brackets 274 extend beyond shaft 273 for attachment to horizontal tie-bars 289 and 290 (Figs. 8 and 14), and these serve as supports for vertical angle plates 291 and 292 (Fig. 14) from which, as shown in Fig. 8, brackets 293 extend forward and upward and brackets 294 extend forward and downward for attachment to circular guard strips 295 which cover the driving sprockets on shaft 273, and also extend beneath plate 287, but spaced therefrom, to form guiding channels for the chain 271 and the pusher 105 fingers, as shown in Fig. 15.

Tie-bars 289 and 290 also support brackets 296 and 297 fastened by bolts and slots to permit their independent vertical adjustment, and it is to these brackets that the 110 forward ends of the top and bottom cam plates 286 and 287 are attached, and by which their distance apart at their forward ends can be adjusted. These plates are cut away or narrowed at their extreme forward 115 ends sufficiently to clear driving sprockets 272 between which they pass, as shown in Fig. 14.

When the pusher is in action, the L-shaped fingers travel with the same, or nearly the same lineal speed as the converging belts, and when properly timed, will be in contact, or nearly so, with the sheets while they are being bowed into arched form by the converging conveyer. It is, however, the particular function of these fingers to give a positive transference or delivery of the arched sheets from the discharge end of the converging conveyer and over guide plates 265 and onto the furnace conveyer by press- 125 130

ing or striking against the rear end of the sheet as soon as it comes to rest in the stationary guides, or even before it has come to rest, if desired. By having these fingers 5 provided with cam rollers, as shown and described, each roller will keep its finger in substantially vertical position until after it moves out of contact with the arched sheet, for as shown in Fig. 8, the pushing finger 10 leaves contact with the delivered sheet by a substantially vertical movement induced by the shape of the curved cam casting 288 on which its roller 285 bears. This eliminates any tendency to lift or kick up the rear end 15 of the arched sheet, and leaves the sheet reliably gripped by the furnace conveyer. Because of their arched shape and therefore somewhat tensional condition, the sheets, even if of thin metal, do not sag or collapse 20 when subjected to the high heat of the furnace.

The furnace conveyer whereby the sheets are taken from the coating machine and its transfer mechanism and delivered into and 25 through the furnace (not shown), is of special construction, as shown in Figs. 20 to 23 inclusive. The conveyer comprises two parallel chains each of which consists of parallel links 475 and 476 connected at their ends 30 by transverse pins 477 on each of which is a roller whereon the chain may travel. Each alternate inner link 475 has a laterally projecting ear 478 and to this end the corresponding ear of the opposing link is secured 35 by bolts 479 the horizontally bent ears of a conveyer flight 480. Each flight comprises a horizontal bar with upturned ends 481, the inner edges of which are knife edges. Adjacent these knife edges, the outer ends of 40 the horizontal bar are shaped to knife edges at 482 (Fig. 21). These flights are considerably wider than the pair of chains by which they are driven and are carried well above the chain rollers by the supporting 45 ears at which they are bolted to the chains.

By making these conveyer flights with knife edges, as shown and described, they have but limited area of contact with the arched sheets delivered to the conveyer by 50 the converging conveyer and pusher of Fig. 5, and although the furnace conveyer flights engage the arched sheets only at their edges, they securely hold those sheets in arched form during transportation to and through 55 the furnace. There is a trackway 483 (Fig. 7) leading toward the intake end of the furnace and consisting of a pair of angle bars adjustably supported as shown, and over these bars the endless furnace conveyer rolls. 60 All of the moving elements above described are preferably driven by a single prime mover such as a variable speed electric motor 492. (Fig. 7). This motor is provided with a pinion 493 meshing with a 65 spur gear 494 on one end of a transverse

shaft 495, the other end of which carries a pinion 496 meshing with a spur gear 497 on a second transverse shaft 498 on which the driving sprockets 499 for the furnace conveyer are fastened. This shaft 498 also carries a gear 500 which meshes with a gear 501 on a stub shaft 502 (Fig. 5), and it is from this stub shaft and its sprocket 503 that the coating machine and the converging conveyer and pusher are driven through chain 75 178, as heretofore described.

By thus driving all of the machines and mechanisms from a single motor, all of the moving elements are properly timed in their movements, and the coated sheets travel 80 through at a definite and predetermined rate and one best suited to the changes which are to be effected within the furnace. By using a variable speed motor the time of transit through the furnace can be changed to suit 85 changes in gage of the sheets under treatment or variations in the duration of treatment as occasion may require. The coating machine can be unclutched and stopped while the furnace conveyer continues to 90 travel through the furnace, and this contributes to convenience of operation and flexibility of control. All of the clutches are of the single jaw type to insure correct timing of the several parts after each disconnection and reconnection of the clutches. 95

The coating machine and its adjuncts above described may be varied in many ways without departing from the spirit of my invention, as defined by the appended claims. 100

I claim:

1. In an apparatus for coating sheet metal, the combination of coating rolls between which a flat sheet may be passed to receive a viscous coating, means for receiving, forwarding and bending said sheet without defacement of the viscous coating, converging belts positioned to engage the side edges of the sheet and squeeze inward thereon to bow said sheet into an arch while the sheet is 110 being carried forward, and pushing means for delivering said sheet beyond said converging belts.

2. In an apparatus for coating sheet metal, the combination of coating rolls between 115 which a flat sheet may be passed to receive a viscous coating, means for receiving, forwarding and bending said sheet without defacement of the viscous coating, converging belts positioned to engage the side edges of the sheet and squeeze inward thereon to bow said sheet into an arch while the sheet is being carried forward, pushing means for delivering said sheet beyond said converging belts, and driving means common to said 120 converging belts and to said pushing means to insure correct timing of the pusher.

3. In an apparatus for coating sheet metal, the combination of coating rolls between 125 which a flat sheet may be passed to receive 130

a viscous coating, means for receiving, forwarding and bending said sheet without defacement of the viscous coating, and converging belts positioned to engage the side edges of the sheet and squeeze inward thereon to bow said sheet into an arch while the sheet is being carried forward, a guide at the delivery end of said converging belts and pushing means for delivering said sheet beyond said guide.

4. In an apparatus for coating sheet metal, the combination of coating rolls between which a flat sheet may be passed to receive a viscous coating, means for receiving, forwarding and bending said sheet without defacement of the viscous coating, and converging belts positioned to engage the side edges of the sheet and squeeze inward thereon to bow said sheet into an arch while the sheet is being carried forward, a cam-controlled finger for pushing said sheet beyond said converging belts, and means for driving said finger.

5. In an apparatus for coating sheet metal, the combination of coating rolls between which a flat sheet may be passed to receive a viscous coating, means for receiving, forwarding and bending said sheet without defacement of the viscous coating, converging belts positioned to engage the side edges of the sheet and squeeze inward thereon to bow said sheet into an arch while the sheet is being carried forward, a cam-controlled finger for pushing said sheet beyond said converging belts, and driving means common to said coating rolls, said converging belts and said pushing finger.

6. In an apparatus for coating sheet metal, the combination of coating rolls between which a flat sheet may be passed to receive a viscous coating, means for receiving, forwarding and bending said sheet, converging belts positioned to engage the side edges of the sheet and squeeze inward thereon to bow said sheet into an arch while the sheet is being carried forward, pushing means for delivering said sheet beyond said converging belt, and driving means common to said coating rolls, said forwarding means, said converging belts and said pushing means to control and time the movements of the sheet through said apparatus.

7. In a delivery mechanism for coating machines, the combination of a guideway, means for delivering thereto an arched sheet of elastic metal and means movable against the rear edge of said sheet to advance it along said guideway.

8. In a delivery mechanism for coating machines, the combination of a guideway, means for delivering thereto an arched sheet of elastic metal, a conveyer beyond said guideway and having flights adapted to receive said arched sheet and hold it by its edges, and means movable against the rear

edge of said sheet to advance it along said guideway and onto said conveyer.

9. In a delivery mechanism for coating machines, the combination of a guideway adjustable in width, means for delivering thereto an arched sheet of elastic metal and means adapted to contact with the rear edge of said sheet to push it out of said guideway.

10. In a delivery mechanism for coating machines, the combination of a guideway, means for delivering thereto an arched sheet of elastic metal and a pusher for advancing said sheet along said guideway, said pusher comprising endless chains and a finger carried thereby and movable against the rear edge of said sheet.

11. In a delivery mechanism for coating machines, the combination of a guideway, means for delivering thereto an arched sheet of elastic metal, a pusher for delivering said sheet out of said guideway, said pusher comprising endless chains connected together by pivot pins, a pushing finger on each pin and movable against the rear edge of the sheet to deliver it beyond said guideway, and a cam-control for the swinging movements of said fingers.

12. In a delivery mechanism for coating machines, the combination of a guideway, means for delivering thereto an arched sheet of elastic metal, and pushing mechanism for delivering said sheet out of said guideway, said mechanism comprising endless chains spaced apart with pivot pins connecting said chains, an L-shaped finger on each pivot pin and having one arm movable against the rear edge of the sheet to be delivered and the other arm adapted to ride on a cam, and a cam on which said arm rides and shaped to lift the finger from engagement with the sheet by a substantially vertical movement to prevent lifting the rear end of the sheet.

13. In a delivery mechanism for coating machines, the combination of a guideway, means for delivering thereto an arched sheet of elastic metal and a pusher for delivering said sheet out of said guideway, said pusher comprising chain members, a finger pivoted thereto and having an arm provided with a cam-roller and a cam surface controlling the swing of said finger, said finger being movable into contact with the rear edge of the arched sheet to be delivered and being permitted by said cam to move out of contact therewith without lifting the rear end of said sheet.

14. In a delivery mechanism for coating machines, the combination of converging elements between which a sheet of elastic metal may be bent into an arch, and means movable into contact with said arched sheet to deliver it beyond the discharge end of said converging elements.

15. In a delivery mechanism for coating

machines, the combination of converging elements between which a sheet of elastic metal may be shaped into an arch, and a power-driven finger movable into contact 5 with the rear edge of said arched sheet to deliver it beyond the discharge end of said converging elements.

16. In a delivery mechanism for coating machines, the combination of converging 10 elements between which a sheet of elastic metal may be bent into an arch, and a cam-controlled finger movable into contact with the rear edge of said sheet to deliver it beyond the discharge end of said converging 15 elements.

17. In a delivery mechanism for coating machines, the combination of converging belts between which a sheet of elastic metal may be bent into the form of an arch, and 20 a power-driven cam-controlled finger movable into contact with the rear edge of said

sheet to deliver it beyond the discharge end of said converging elements.

18. In a delivery mechanism for coating machines, the combination of a guideway, 25 converging belts for delivering thereto an arched sheet of elastic metal, a pusher for advancing said sheet along said guideway and a driving means common to said belts and said pusher and maintaining proper 30 relative speeds therefor.

19. In a coating machine, the combination of a pair of coating rolls, automatic feeding means for delivering a flat sheet to said rolls, means beyond said rolls for advancing said sheet and shaping it into an arch, pushing means for the further advancement of said sheet, and driving means common to said pushing means and said feeding means and properly timing their movements. 35

In testimony whereof I affix my signature.

WILLIAM E. WATKINS.
